UNITED STATES PATENT OFFICE.

PAUL E. PARKS, OF OAK PARK, AND JOHN VAN VULPEN, OF CHICAGO, ILLINOIS, ASSIGNORS TO VAPOR CAR HEATING COMPANY, INC., OF CHICAGO, ILLINOIS, A CORPORATION OF NEW YORK.

PRESSURE-ACTUATED CIRCUIT BREAKER.

Application filed March 8, 1923. Serial No. 623,602.

Our invention relates to a fluid pressure actuated circuit breaker, and particularly to a device which though normally operated automatically to open and close its circuit in response to the appearance and disappearance of pressure in a conduit or vessel with which the device is associated, may, in the absence of fluid pressure, be operated manually to bring about a breaking of such electric circuit.

One of the principal objects of the invention is to provide a circuit breaker of this type which will be simple in its construction, which will operate reliably and with a minimum of destructive sparking when the circuit is broken, and which can be manufactured at a relatively low cost.

A further object is to provide a circuit breaker of this type which can be manually operated (in the absence of fluid pressure) not only to break the circuit but to close it again after it has been broken through manual operation.

The invention consists in the new and improved arrangements, devices and constructions shown in the drawings annexed hereto and to be hereinafter described and claimed for carrying out the aforesaid objects and such other incidental objects as will be mentioned in the following description of the preferred form of the invention illustrated in the drawing.

In the drawings,

Fig. 1 is a fragmentary side elevation of the circuit breaker and the cabinet in which it is contained, the switch or bridging member of the device being shown in one of its two circuit breaking positions.

Fig. 2 is a plan view of the mechanism shown in Fig. 1 but with the bridging member in its circuit closing position.

Fig. 3 is a sectional view on line 3—3 of Fig. 2.

Fig. 4 is a sectional view on line 4—4 of Fig. 3, and

Fig. 5 is a view, in perspective, of one of the contact springs forming part of the circuit breaker.

Like characters of reference designate like parts in the several figures of the drawings.

Referring to the drawings, 10 designates

a casing for containing the circuit breaking mechanism. Secured to the bottom 11 of the casing is an insulating block 12 to the upper and lower faces of which are secured a pair of contacts 13 and 14 (Fig. 5) to which are connected, respectively, wires 15 and 16. A sheet of insulating material 17 is interposed between the lower contact 14 and the base 11 of the cabinet. 18 designates a screw for fastening the block 12 to the base 11, the contact 14 being thereby held in place. 19 is a screw for securing the contact 13 to the upper face of the block and 20, 21 are binding posts for the wires 15 and 16.

The contacts 13 and 14 have spring portions 22, 23 which project outwardly in diagonal directions from the front face of the block and have their adjacent extremities 24, 25 bent backwardly toward the face of the block. The gap thus formed is closed by means of a sleeve 26 carried on a rocking member or lever 27 which is preferably channel-shaped and is pivoted, by pivot stud 28, to an upstanding yoke 29 having flanges 30 secured to the base 11 of the cabinet. The sleeve 26 surrounds a roller 31 which turns on a stud 32 extending through the side flanges 33, 33 of the rocking member 27. The sleeve or metal roller 26 surrounding the insulating roller 31 is kept from contact with the flanges 33 by washers 34 of insulating material.

The flanges 33 of the rocking member 27 are formed at the forward end of the rocking member with extensions 35 having slots 36 through which slots projects a stud 37 extending also through a perforation in the lower end of a pull rod and plunger 38 which is guided for vertical movement in a bushing 39 on the top plate 40 of the cabinet 10.

The cabinet 10 is shown as arranged in a larger box 41 and secured to the bottom of the box 41 is a pneumatic cylinder 42 having arranged therein a piston 43. The piston 43 has secured thereto a stem 44 which projects into the bottom of the cabinet 10 through a boss 45 which is on the upper end of the cylinder and is fitted into an opening through the bottoms of box 41 and cabinet 10. The piston 43 is fitted with a leather gasket 46 which is held in place.

25 by a cup 47 clamped against the leather by means of a nut 48 on the threaded end 49 of stem 44, the stem itself being secured to the piston by nut 48. When the piston is 5 in its lower position the end 49 of stem 44 rests upon a projection 50 on the bonnet 51 which closes the outer end of the cylinder. At one side of the cylinder is a hollow structure 52, preferably cast integral with the 10 cylinder into the bottom of which is threaded a pipe 53. The chamber 54 in the structure 52 communicates through port 55 with the chamber 56 below piston 43. A coiled spring 57 is interposed between the piston 43 and the upper end of cylinder 42. The upper face of the piston is preferably provided with a gasket 58, seated in a suitable recess, which gasket is adapted to bear against a circular rib 59 formed on the upper 15 end of the cylinder to prevent leakage of fluid pressure when the piston is raised. 60 is a coiled spring centered by a stud 61 on the base 11 with its upper end arranged to bear against the under side of the rocking member 27.

30 *Operation.*—In the absence of fluid pressure against the under side of piston 43, gravity and the action of spring 57 keep the piston in its lower position as shown in Figs. 3 and 4. In this position the upper end of the stem 44 stands at some distance below the outer end of the rocking member 27. The inner end of the rocking member is held up by spring 60 so that the roller 26 35 occupies a circuit closing position in the gap between the contact springs 22 and 23. The contact springs will be slightly flexed toward the face of block 12 so as to insure proper contact.

40 When fluid pressure is introduced into the chamber 56 from pipe 53 through chamber 54 and port 55 the piston 43 is raised compressing spring 57 which brings the stem 44 into contact with the outer end 45 of the rocking member 27 which is turned on its pivot so that the roller 26 moves downwardly on the contact spring 23 flexing it toward the block and compressing the coiled spring 60. This position of the rocking member and associated parts is shown in dotted lines in Fig. 1 and involves breaking the circuit through wires 15 and 16. As soon as the pressure back of piston 43 disappears spring 60 reacts to return the rocking member to its horizontal or circuit closing position with the roller 26 in the gap between contact springs 22 and 23.

55 In order to break the circuit by manual operation of the device pull rod 38 is raised 60 so as to swing the rocking member 27 in the upward direction to raise the roller 26 away from the gap between the contact springs 22 and 23 as shown in Fig. 1. The roller rides over the bend in spring 22 in 65 making this movement and the bent shape

of the spring holds the rocking member in this tilted position. As soon, however, as the piston 43 is again subjected to fluid pressure the stem 44 on the piston will engage the outer end of rocking member 27 and 70 swing the same so as to move the roller across the gap between the contact springs 22 and 23 and below said gap, the circuit being closed only momentarily during this movement. If in the meantime it is desired to close the circuit this may be done by depressing plunger 38.

75 The spring 60 is designed so that it will exert force enough to move the rocking member from its tilted down position to its horizontal or circuit closing position against the force exerted by the lower contact spring 23 but in the circuit closing position of the rocking member the spring is compressed but little if any so that it has no appreciable 80 tendency to lift the rocking member above the gap.

85 When the roller is moved into and out of the gap it has a wiping action on the contact springs which besides keeping the 90 springs clean produces a rotation of the roller so that its points of contact with the springs vary. The rocking movements of the bridging member 27 are limited by contact of the bridging member with the upper 95 edges of the yoke 29.

100 The circuit breaker of our invention is intended particularly for use in connection with a heating system having two thermostats, one of which maintains a temperature of the apartment heated of 70° Fahrenheit while the other maintains a temperature of 50°. The low temperature thermostat, in the particular arrangement contemplated, is put into control by closing the circuit governed by the circuit breaker which is the subject matter of this application while the high temperature thermostat is put into control of the system by breaking this circuit. For that reason the plunger 38 bears 105 the numeral 50 to indicate the closure of the circuit and the numerals 70, 70 which, when either of the positions are directly above the upper edge of the bushing 39, indicate that the circuit governed by the circuit breaker 110 is broken. Our invention, however, is capable of other uses than that just referred to.

115 While we have described our invention in a preferred embodiment, it will be understood that we contemplate any and all structural modifications within the scope of the annexed claims.

120 We claim:

125 1. A circuit breaker comprising, in combination, a pair of spaced contact springs, a bridging member adapted to be interposed in the gap between said springs, a fluid pressure actuated device for moving said bridging member in one direction out of said gap, and manually operated means for moving 130

- the bridging member out of said gap in the other direction.
2. A circuit breaker comprising, in combination, a pair of spaced contact springs, 5 a bridging member adapted to be interposed in the gap between said springs, a fluid pressure actuated device for moving said bridging member in one direction out of said gap, manually operated means for moving the 10 bridging member out of said gap in the other direction, and a spring tending to hold the bridging member in said gap against the action of said fluid pressure actuated device.
3. A circuit breaker comprising, in combination, a pair of spaced contact springs, a pivoted bridging member adapted to be interposed in circuit closing position in the gap between said springs, a fluid pressure actuated device for rocking said member in 15 one direction out of said gap, and manually operated means for rocking said member out of the gap in the other direction.
4. A circuit breaker comprising, in combination, a pair of spaced contact springs, a bridging member comprising a lever and a roller thereon which is adapted to be interposed in the gap between said springs, a fluid pressure actuated device for moving said bridging member in one direction out 20 of said gap, and manually operated means for moving the bridging member out of said gap in the other direction.
5. A circuit breaker comprising, in combination, a pair of spaced contact springs, a bridging member adapted to be interposed in circuit closing position in the gap between said springs, a fluid pressure actuated device for moving said bridging member in one direction out of said gap, and a pull rod 25 connected with said member for moving the same out of the gap in the opposite direction one of said contacts being formed to hold the bridging member in the last mentioned position.
6. A circuit breaker comprising, in combination, a pair of spaced contact springs, a bridging member adapted to be interposed in circuit closing position in the gap between said springs, a fluid pressure actuated device for moving said bridging member in one direction out of said gap, a pull rod 30 connected with said member for moving the same out of the gap in the opposite direction, and a spring tending to hold said bridging member in its circuit closing position against the action of the fluid pressure actuated device.
7. A circuit breaker comprising, in combination, a pair of angularly disposed spaced contact springs, having their adjacent extremities curved backwardly into the gap between such springs, and a rocking member provided at one end with a roller adapted to fit into the gap between said springs to 35 complete the circuit, and movable in either direction from the gap by a rolling motion along one or the other of the curved spring ends, the spring end being flexed back to permit the roller to pass from the gap and subsequently engaging the roller and tending to hold the roller in this circuit breaking position.
8. A circuit breaker comprising, in combination, a pair of angularly disposed spaced contact springs having their adjacent extremities bent backwardly into the gap between said springs, a rocking member provided at one end with a roller adapted to fit into the gap between said springs, a fluid pressure actuated device for rocking 40 said member in one direction out of the gap, and a pull rod for rocking said member out of the gap in the other direction.
9. A circuit breaker comprising, in combination, a pair of angularly disposed spaced contact springs having their adjacent extremities bent backwardly into the gap between said springs, a rocking member provided at one end with a roller adapted to fit into the gap between said springs, a fluid pressure actuated device for rocking 45 said member in one direction out of the gap, a pull rod for rocking said member out of the gap in the other direction, and a spring which tends to hold the rocking member in its circuit closing position against the action of said fluid pressure actuating device.
10. A circuit breaker comprising in combination, a pair of angularly disposed spaced contact springs, having their adjacent extremities curved backwardly into the gap between said springs, and a rocking contact member having an end portion adapted to fit into the gap between the spring ends to complete the circuit, and movable in either direction from the gap by forcing back one of the curved spring ends, which spring end subsequently engages the movable contact member and tends to hold same yieldably in this circuit breaking position.
11. A circuit breaker comprising, in combination, a pair of spaced contact springs and a bridging member which is pivoted and provided with a roller adapted to be interposed in the gap between said springs so as to have a wiping contact with the springs when moved into and out of its circuit closing position, one of said springs being formed so as to bear against and hold said bridging member in one of its circuit breaking positions.
12. In a circuit breaker, the combination of a pair of spaced contact springs, a pivoted bridging member, a contact roller on said bridging member adapted to be interposed in circuit closing position in the gap between said contact springs, a spring tending to move said bridging member from a circuit breaking position against one of said springs.

- into the gap between said springs, mechanism for moving the bridging member out of the gap in the direction of said last mentioned spring, and manually operated means 5 for moving said bridging member out of the gap in the direction of the other spring.
13. In a circuit breaker, the combination of a pair of spaced contact springs, a pivoted bridging member, a contact roller on 10 said bridging member adapted to be interposed in circuit closing position in the gap between said contact springs, a spring tending to move said bridging member from a circuit breaking position against one of said 15 contact springs into the gap between said contact springs, mechanism for moving the bridging member out of the gap in the direction of said last mentioned spring, and manually operated means for moving said 20 bridging member out of the gap in the direction of the other spring, said last named spring being formed so as to hold said bridging member in said last named circuit breaking position.
14. A circuit breaker comprising, in combination, a pair of spaced contacts and a member to bridge the gap between the same which is bodily movable out of said gap and out of engagement with one or the other 25 of the contacts in opposite directions, one of said contacts consisting of a spring flexed by movement of the bridging member out of the gap and having a configuration whereby it holds said bridging member in its circuit 30 breaking position on that side of the gap.
15. A circuit breaker comprising, in combination, a pair of spaced contacts and a member to bridge the gap between the same which is movable out of said gap in opposite 40 directions, one of said contacts consisting of a spring having a configuration whereby it holds said bridging member in its circuit breaking position on that side of the gap, and a spring which tends to move said bridging member into said gap from the direction 45 of the other contact.
16. In a circuit breaker, the combination of a pair of spaced spring contacts, a member to bridge the space between said contacts, manually operated means for moving said 50 bridging member out of said gap and along one of said contacts, mechanism for moving said bridging member from said last named position, or its position in said gap, to a position on the other side of said gap and hold it there, and a spring which tends 55 to move said bridging member from the position last mentioned into the gap.
17. In a circuit breaker, the combination of a pair of spaced spring contacts, a member to bridge the space between said contacts, manually operated means for moving said 60 bridging member out of said gap and along one of said contacts, fluid pressure actuated 65 mechanism for moving said bridging mem-
- ber from said last named position, or its position in said gap, to a position on the other side of said gap, and a spring which tends to move said bridging member from the position last mentioned into the gap. 70
18. In a circuit breaker, the combination of a pair of spaced spring contacts, a member to bridge the space between said contacts, manually operated means for moving said bridging member out of said 75 gap and along one of said contacts, said contacts being formed so as to hold the bridging member in said circuit breaking position, mechanism for moving said bridging member from said last named position, or its position in said gap, to a position on the other side of said gap, and a spring which tends to move said bridging member from the position last mentioned into the gap. 80
19. A circuit breaker comprising, in combination, a pair of spaced contact springs, a pivoted bridging member, a contact roller on one end of said member adapted to bridge the gap between said contact springs, a fluid pressure cylinder, a piston in said cylinder 90 having a stem spaced from the bridging member when the latter is in its circuit closing position and there is no fluid pressure in the cylinder, and adapted to be thrust against the bridging member when the fluid pressure is introduced into the cylinder to move said bridging member out of the gap between said contact springs, a spring which returns said bridging member to its circuit 95 closing position when pressure in the cylinder disappears, and manually operated means for rocking the bridging member out of the gap in the direction opposite to that of its movement under action of said piston, the contact spring at this side of the gap 100 being formed so as to hold said bridging member in said last named circuit breaking position. 105
20. A circuit breaker comprising, in combination, a pair of spaced contact springs, a bridging member adapted to be interposed in the gap between said springs, a fluid pressure actuated device for moving said bridging member in one direction out of said gap, and manually operated means for moving the bridging member out of said gap in the other direction and for returning same to its bridging position. 110
21. A circuit breaker comprising, in combination, a pair of spaced contact springs, a bridging member adapted to be interposed in circuit closing position in the gap between said springs, a fluid pressure actuated device for moving said bridging member in one direction out of said gap, and an operating element connected with said member for moving the same out of the gap in the opposite direction and for returning the same to its bridging position. 115
22. A circuit breaker comprising a mov- 120
- 125
- 130

- able contact member adapted to assume different positions for making and breaking a circuit, a fluid pressure device for controlling the movements of said contact member, 5 and manually operable means operable only in the absence of fluid pressure in said fluid pressure device for moving said contact member back and forth between its make and break positions.
- 10 23. A circuit breaker comprising a movable contact member adapted to assume different positions for making and breaking a circuit, a fluid pressure device which when subject to fluid pressure moves the contact member to break the circuit, means for automatically returning the contact member to a circuit making position in the absence of fluid pressure in the device, and manually operable means, operable only in the absence 15 of fluid pressure in said fluid pressure device for moving said contact member from a making to a breaking position and from a breaking to a making position.
24. In a circuit breaker, a pair of spaced contact springs and an oscillatory bridging member bodily movable in either direction out of the gap between the contact springs so as to contact with only one of the springs, the latter being formed so as to flex with the 25 oscillatory movements of the bridging member thereby tending to hold said member in the gap or at either side thereof to which it may have been moved.
25. A circuit breaker comprising a pair 30 of spaced fixed contacts, a bridging member movable out of the gap between said contacts in opposite directions, means tending to move said bridging member into the gap from one side thereof, a fluid pressure device which when under pressure moves said member to the off position on the aforesaid side of the gap from either of its other positions, and means, operable only in the absence of pressure in said device, for moving said member in either direction between the gap and the other off position.
- 35 26. A circuit breaker comprising a pair of spaced fixed contacts, a bridging member movable out of the gap between said contacts in opposite directions, means tending to move said bridging member into the gap from one side thereof, a fluid pressure device which when under pressure moves said member to the off position on the aforesaid side of the gap from either of its other positions, and means, operable only in the absence of pressure in said device, for moving said member in either direction between the gap and the other off position.
- 40 27. A circuit breaker comprising a movable contact member adapted to be moved from a circuit making position to either of two different circuit breaking positions, automatically operable means for moving the contact member to one circuit breaking position and holding it there, and manually operable means operable only when the automatic means is inoperative for moving said contact member to and from its circuit making position and the other circuit breaking position.
- 45 28. A circuit breaker comprising a movable contact member adapted to be moved from a circuit making position to either of two different circuit breaking positions, a fluid pressure operated device for moving the contact member to one circuit breaking position, means operable in the absence of fluid pressure to return the contact member to contact making position, and manually operable means operable only in the absence of fluid pressure in the fluid pressure operated device for moving the contact member to and from its circuit making position and the other circuit breaking position.
